(57) **CLAIM**

The ornamental design for a tag for tissue biopsy, as shown and described.

DESCRIPTION

FIG. 1 is a front perspective view of a tag for tissue biopsy showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The portions shown in broken lines form no part of the claimed design. The dot-dash boundary line represents the boundary between the claimed design and the unclaimed design; the dot-dash boundary line itself forms no part of the claimed design.
